UNITED STATES PATENT OFFICE.

CALLIE MARILIS GRAHAM, OF ORACLE, ARIZONA.

DESIGN FOR A PIN OR BADGE.

60,232.

Specification for Design.

Patented Jan. 17, 1922.

Application filed September 20, 1920. Serial No. 411,669. Term of patent 3½ years.

To all whom it may concern:

Be it known that I, CALLIE MARILIS GRAHAM, a citizen of the United States, residing at Oracle, in the county of Pinal and State of Arizona, have invented a new, original, and ornamental Design for a Pin or Badge, of which the following is a specification, reference being had to the accompanying drawing, forming part thereof.

The figure is a plan view of a pin or badge showing my new design.

I claim:

The ornamental design for a pin or badge as shown.

CALLIE MARILIS GRAHAM.
